UNITED STATES PATENT OFFICE.

CHARLES F. KETTERING, OF DAYTON, OHIO, ASSIGNOR TO THE DAYTON ENGINEERING LABORATORIES COMPANY, A CORPORATION OF OHIO.

IGNITION SYSTEM FOR COMBUSTION-ENGINES.

1,255,177.

Specification of Letters Patent. Patented Feb. 5, 1918.

Application filed July 29, 1914. Serial No. 853,789.

To all whom it may concern:

Be it known that I, CHARLES F. KETTERING, citizen of the United States of America, residing at Dayton, county of Montgomery, 5 and State of Ohio, have invented certain new and useful Improvements in Ignition Systems for Combustion-Engines, of which the following is a full, clear, and exact description.

10 This invention relates to ignition systems for internal combustion engines, being an improvement in devices intended for this purpose which is automatic in operation and designed to effect the most advantageous ignition during the operation of the engine for all speeds at which it may be running.

15 It is well known that one obstacle to the economic operation of such engines when subject to constantly varying speeds is the lack of proper provision for varying the movements of ignition according to the variations in the speed. Under certain conditions of operation, particularly in starting, 20 the usual manually operated spark control is sufficient, if not necessary, and my improvements contemplate the use of such devices as heretofore; but as such devices require for their most efficient operation the 25 constant attention of the operator, the improved device which I have designed is intended to supplement the effect of such manual means by automatically varying the time 30 of the occurrence of the spark, according to the speed of the engine, so that at all times the most favorable ignition conditions will 35 be maintained without the attention of the operator.

40 One of the features of this combined automatic and manual control is that the range of the automatic control may be changed by the manual operation; so that the complete range of automatic control may be started from different points by the adjustment of 45 the manual means.

45 In the operation of internal combustion engines, it has been found that a greater variation in the time of occurrence of the spark in the ignition system is required to 50 efficiently provide ignitions for engine speeds varying from zero to an intermediate speed, than is required for engine speeds ranging from an intermediate to a maximum point, and one of the results of my improvement is the provision of a means,

5 whereby a greater variation in the time of the occurrence of the spark will take place during the range of engine speed from zero to an intermediate point, than occurs for speeds ranging from an intermediate to a maximum speed.

Automatic devices responsive to variations in engine speed, which control the ignition system in various ways, have heretofore been employed both with and without the usual 65 manually controlled mechanism, so that my invention hereinafter to be described will be found to reside in the novel construction of my device rather than in its general function. 70

In the accompanying drawings:

75 Figure 1 is a vertical sectional view of an improved distributing and spark timing apparatus constructed according to my invention.

Fig. 2 is a view, partly in section and partly in side elevation, of the same mechanism.

Fig. 3 is a top plan view of the timer casting, showing the arrangement of the timer 80 can and cooperating contacts.

Fig. 4 is a detail view in perspective of part of the interior mechanism of the device.

Fig. 5 is a detail view of the ring governor member. 85

Figs. 6, 7 and 8 are detail perspective views of certain of the parts of the device to be more fully hereinafter described.

In the drawings, to which reference will 90 now be made, the numeral 1 indicates the casing containing the instrument and which, in practice, is mounted in the most advantageous position possible with respect to the engine with which it is designed to be used.

A shaft 2 revolved by and synchronously 95 with the main shaft of the engine extends through an opening in the bottom of the casing, and terminates in the bifurcated or slotted end portion 3, the slot being designated by the numeral 4, and works in a hollow sleeve 5, which constitutes the distributor or timer shaft, inasmuch as adjacent to its upper end the timer cam 6 is secured, while its extreme end is connected with and serves to rotate the rotor 7 of the usual distributor 8. 100

The ignition timing and distributing mechanism, including the timer contacts and the actuating cam in connection with the distributing system, are now well un- 105-110

derstood by those skilled in the art, and therefore require no specific description in connection with the operation and relations of the contact arm 9 between the timer cam 6 and the fixed contact pin 10.

The distributor shaft 5 is provided at its upper and lower ends, with ball or roller bearings 11 which are secured within the upper and lower walls of the timer casing 1 and are securely held in place by lock nut 12, which has a screw threaded engagement with the lower end of the outer sleeve or shaft 5.

A collar 13 loosely surrounds the shaft 5 and is provided with an annular groove, 15 wherein are located lugs or rollers 15, Fig. 8, which, in turn, are carried by the yoke member 16. This yoke member is secured to the rod 17, pivotally mounted in the casing 1, and extending out from the same, to connect with any suitable manual device for effecting the adjustment of the collar 13 through the movement of the yoke member 16.

The collar 13 has a pair of upright arms 18, to the upper ends of which there is pivoted, as shown at 19 in Fig. 2, a ring member 20. The arms 18 are provided with slots 21, through which passes a transverse pin 22, which also extends through the lower 30 portion of a collar 23, as well as through a spiral slot 24 cut or formed in the distributor shaft 5, and the straight slot 4 in the shaft 2. From Fig. 6, which is a detail perspective view of this pin 22, it will be seen that 35 the intermediate portion of the same which fits the straight slot 4 of shaft 2 is reduced in thickness and is rectangular in cross-section. The same is true of the end of the pin which fits the rectangular slot 21, formed 40 in one of the uprights 18. This reduction in size and peculiar formation of the intermediate and one of the end portions of the pin 22 facilitates the assembling of certain of the co-operating elements and also tends 45 to lock the pin in applied position, but in order to insure the pin against accidental displacement a cotter pin 25, or other suitable stop element, may be secured in the reduced or flattened end of the same at 26.

50 The collar 23 is normally maintained in position below the axis of the ring member 20, by means of a spiral spring 27, interposed between a fixed stop near the top of the shaft 5 and the top of the collar. The collar 55 23, as has heretofore been stated, carries the transverse pin 22, and upon any vertical movement of the collar, either under control of the automatic governor member 20, which when rotated tends to assume a horizontal position, or through the adjustment of the timer mechanism hereinbefore set forth, will cause a movement of the distributor shaft 5, relative to the normal position thereof and its rotation transmitted by 60 the driving shaft 2.

Consequently, any movement of the sleeve 5 relative to the shaft 2, and to its normal rotation, will effect a corresponding relative movement between the timer cam 6 and the shaft 2, and distributor rotor 7 and the 70 shaft 2.

In order that the ring or governor member 20 may control the movement of the collar 23, and the pin 22, and thus control the advance or retardation of the timer cam and 75 rotor of the distributor, a positive connection between the ring 20 and the collar 23 is necessary. One way of accomplishing this is clearly shown in Fig. 1, wherein a stud or projection 28 is rigidly secured to the ring 80 20, and has its free end engaging the annular groove 29 in the collar 23, thus permitting a free rotatable movement of the collar, but effecting a concurrent movement of the collar in accordance with the vertical move- 85 ment of the governor ring.

From the peculiar nature of the spring 27 and the structure of the ring 20, it results that the initial tendency of the ring will be to move more rapidly at the start and during the earlier stages of its operation, as when it is approaching a point of balance, when the tension of the spring is increasing. This will give exactly the result desired, inasmuch as when the engine starts from an extremely low speed and is brought up to normal driving speed, a much greater adjustment or regulation of the time of sparking must occur, as compared with the adjustment 100 necessary for the change from normal driving conditions to extremely high speeds.

While the form of mechanism herein shown and described constitutes a preferred form of embodiment of the invention, it is 105 to be understood that other forms might be adopted, all coming within the scope of the claims which follow.

What I claim is:

1. In an ignition system for combustion 110 engines, the combination with a driving shaft, a sleeve connected therewith; a plurality of collars; an arm connected to one of said collars, a pin connected to said arm and passing through an angular slot in the sleeve 115 and a longitudinal slot in said shaft; a governor mounted on the above mentioned arm and connected with said collar; a regulating spring for resisting said governor; and means for adjusting one of the other collars 120 longitudinally on said sleeve.

2. In an ignition system, the combination with a set of contact elements operable to open and close an ignition circuit; of a driven timer cam to operate said contact elements; automatically controlled mechanism operable to advance the timer cam throughout a determined range of movement relative to its ordinary movement to vary the timing of the sparking impulses; and man- 130

ually controlled means for adjusting the timer cam relative to its ordinary movement without affecting the operative range of movement of the speed controlled mechanism.

3. In an ignition system, the combination of a set of contact elements operable to open and close an ignition circuit; of a driven timer cam to operate said contact elements; 10 automatically controlled mechanism for advancing the timer cam throughout a determined range of movement relative to the ordinary movement of said cam to vary the timing of the sparking impulses; and manually controlled means for actuating the automatically controlled mechanism to adjust the timer cam relative to its ordinary movement without affecting the adjusted position of the automatically controlled mechanism.
- 20 4. In an ignition system, the combination of a set of contact elements operable to open and close an ignition circuit; of a timing device operable to actuate said contact elements; automatically controlled mechanism to adjust said timing device throughout a determined range of movement relative to its ordinary movement; and manually operable means for adjusting the timing device relative to its ordinary movement to vary 30 the timing of the sparking impulses, said manually operable means being effective to adjust the timing device irrespective of the point of adjustment effected by the automatically controlled means without altering 35 the range of movement of the automatically controlled means.
5. In an ignition system for combustion engines, the combination with a driving shaft, a sleeve connected therewith; a timer cam associated with said sleeve; a collar; an arm connected to said collar; a pin con-

nected to said arm and passing through an angular slot in the sleeve and a longitudinal slot in said shaft; a governor mounted on the above mentioned arm and connected with said collar; a regulating spring for resisting the movement of said governor; and means independent of said governor for adjusting said collar longitudinally on said sleeve and thereby effecting relative movement between the timer cam and the driving shaft, and also compressing said regulating spring, whereby to increase the resistance of said spring relative to the actuation of the governor.

6. In an ignition system, the combination with automatically controlled mechanism for varying the time of the sparking impulses in an ignition circuit including a cam carrying sleeve provided with a spiral slot; an engine driven shaft provided with a straight slot; a pin passing through both of said slots; an adjustable collar mounted on said sleeve and carrying said pin; a second collar mounted on said sleeve and having projecting arms provided with slots within which said pin slidably fits; a governor pivotally mounted on said arms and actuated with the adjustable collar; and manually controlled means to actuate the second collar, the governor, the adjustable collar, and the pin, to effect relative movement between the cam carrying sleeve and the engine driven shaft without affecting any previous adjusted position of the centrifugal governor.

In testimony whereof I affix my signature in the presence of two subscribing witnesses.

CHARLES F. KETTERING.
